UNITED STATES PATENT OFFICE

ARCHIE REXALD WOLFE, OF SUMMIT, NEW JERSEY

ELECTRIC CONNECTION PLUG

Application filed June 27, 1929. Serial No. 374,199.

(GRANTED UNDER THE ACT OF MARCH 3, 1883, AS AMENDED APRIL 30, 1928; 370 O. G. 757)

My invention relates to improvements in non-screw electric light plugs adapted to engage and make electrical connection to the standard screw rim electric light socket without screwing the latter or said plug, and the objects of said improvements are, first, to provide in a non-screw plug a means for attaching and detaching the screw rim of the standard screw rim electric light socket without screwing the latter or said plug, and a separate means for assuring electrical contact between the center contact of said plug and the center contact of said socket by vertically elevating said attaching and detaching means before the latter can be attached to said screw rim and by vertically lowering or depressing by spring force said attaching and detaching means after the latter has been attached to said screw rim; second, to provide in a non-screw electric plug a means for receiving, engaging and electrically connecting the standard electric light plug attachment; third, to produce a non-screw electric plug readily designed to be equipped with terminal posts and a bottom cap for direct connection to the terminal wires of portable electric lamps, toasters, etc.; and fourth, to obviate the necessity of one of the elements, namely, "the movable center contact", in a non-screw plug, described in my application for Letters Patent of the latter Serial No. 344,890, filed March 6, 1929.

One form of my invention is illustrated in the accompanying drawing, in which, Fig. 1, is a plan view of the inner half of the device; Fig. 2, is a view of the upper side of the depressing spring 20; Fig. 3, is a vertical sectional view of the invention on the broken line 1-1, Fig. 1; Fig. 4, is a vertical sectional view on the broken line 2-2, Fig. 1; Fig. 5, is a view of the upper side of the elevating cam 25, and its insulation handle 29; Fig. 6, is a plan view showing the metal bedplate 15, in place in the upper side of the lower section 3, of the insulation body; Fig. 7, is a view of the outer face of the spring jaw 9; Fig. 8, is a view of the bottom of the invention; and Fig. 9 is a perspective view 50 of the interior members of the plug.

Similar numerals refer to similar parts throughout the several views.

The upper section 1, middle section 2, and lower section 3, of the insulation body are clamped rigidly together by means of the tie bolts 4, and 5, which are secured by the threaded nuts 6, and 7, respectively. The latter are countersunk into the bottom of said section 3.

The cavity 8, in said section 3, accommodates the lower portions of the reverse acting spring jaws 9, and 10, the lower ends of which are rigidly affixed to the vertical guide 11. The lower end of the latter projects into the cavity 12, and is limited to vertical movement with respect to said body.

Said jaws 9, and 10, project upward through the apertures 13, and 14, respectively, in the metal bedplate 15, which is countersunk into the upper end of said section 3, and is secured in place by means of the tie bolts 4, and 5, which clamp the upright cylindrical bushings 16, and 17, respectively, between said section 2, and bedplate 15. Said bolts 4, and 5, pass through apertures in said bushings and the apertures 18, and 19, respectively, in said bedplate 15.

The depressing spring 20, is secured to the bottom of said bedplate 15, and is depressed between the latter and the joined ends of the guide 11, and spring jaws 9, and 10, thus tending to keep the latter in the depressed or lowered position. Said spring 20, is enlarged and provided with the slot 21, for accommodating the spring jaw 10. And the cavity 22, in said section 3, accommodates the enlarged portion of said spring 20.

The attachment spring 23, is secured to said bedplate 15, and projects into the attachment aperture 24, in said section 3.

The reciprocable sliding cams 25, and 26, ride upon said bedplate 15, project through the similar rectangular apertures 27, and 28, in said jaws 9, and 10, respectively, and are provided with the insulation handles 29, and 30, respectively, which project on the outside of said section 3, and with the stops 31, and 32, respectively, which retain said cams 25, and 26, in said apertures 27, and 28.

Said jaws 9, and 10, project upward

through apertures 33, and 34, respectively, in said section 2, and into the slots 35, and 36, respectively, in said section 1. The outer face of each of said jaws 9, and 10, is provided near its upper end with raised ribs or threads which are adapted to engage the threads on the interior surface of the screw rim of the standard screw rim electric light socket. The inward movement of said jaws 9, and 10, is limited by the flanges 37, and 38, respectively, and their outward movement is limited by said apertures 33, and 34, respectively.

15 The attachment spring 39, projects into the attachment aperture 40, in said section 3, and is secured to the center contact 41, which projects downward through a central aperture in section 1, and is secured by the nut 42.

20 In the practical operation of said plug, the insulated handles 29, and 30, are simultaneously moved toward each other as far as they will go by a thumb and forefinger of one hand. This movement first actuates the cams 25, and 26, to engage the reverse acting spring jaws 9, and 10, elevating the latter a maximum distance against the tension of the spring 20, immediately after which said handles 29, and 30, collide with said jaws 9, and 10, moving the ribbed ends of the latter toward each other a maximum distance into the slots 35, and 36. The mechanism of said plug is now in position to be inserted

30 in a socket as shown in Figs. 1, 3, 4 and 8, and while in said position the tip or upper portion is inserted into the screw rim of any standard screw rim socket as far as it will go. Said handles 29, and 30 are then released, which first permits the ribbed or

40 threaded ends of said jaws 9, and 10, to move outwardly by their own spring tension into engagement with said screw rim, immediately after which said spring 20, depresses said jaws 9, and 10, which forces said tip of said plug farther into the screw of said

45 socket or until the center contact of the latter collides with and makes electrical contact with the center contact 41, of said plug. Said handles 29, and 30, when released are moved outwardly or away from each other by said spring jaws 9, and 10, and the action of the latter on said cams 25, and 26.

50 One leg of the electric circuit through said plug is completed from the center contact 41, to the attachment spring 39. The other leg is completed from the spring jaws 9 and 10, through spring 20, and bedplate 15, to the attachment spring 23.

55 The invention described herein may be manufactured and used by or for the Government of the United States for governmental purposes without the payment to me of any royalty thereon.

60 I claim:

65 1. In an electric connection, a body, a cen-

ter contact rigidly mounted in said body, laterally and longitudinally transitorily movable arms mounted in the body, and compressible means having an inclined surface engaging with said arms for moving them in said two directions.

70 2. In an electric connection, a body, a fixed center contact, laterally and longitudinally transitorily movable spring arms, means normally holding the arms in one of their longitudinal positions, reciprocally sliding cams for moving the arms longitudinally against the tension of said means, and means for operating the cams and moving the arms laterally.

75 3. In an electric connection, a body, a center contact mounted in the body, arms movable laterally and longitudinally transitorily with respect to said body mounted therein, means normally holding the arms in one of their longitudinal positions, and means for moving said arms laterally and at substantially the same time moving them to another of their longitudinal positions against the tension of said first means.

80 4. In an electric connection, a body, a center contact mounted therein, resilient arms having lateral and longitudinal transitory movement with respect to the body, said arms being held normally in an outer position by their resiliency, a spring for holding said arms in one of their longitudinal positions, means for moving said arms to another of their longitudinal positions, and means for moving said arms laterally against their outward tendency.

85 5. In an electrical connection, a body, a center contact mounted therein, laterally and longitudinally transitorily movable arms supported in the body, said arms being adapted to engage an attachment to be secured to said plug, means for operating said arms, and means for moving the plug further into said attachment after the said first means has been released.
